UNITED STATES PATENT OFFICE.

EDWARD ROSELL MCKINZIE, OF MEMPHIS, TENNESSEE.

LOCK-SWITCH.

1,101,870.

Specification of Letters Patent. Patented June 30, 1914.

Application filed December 8, 1913. Serial No. 805,280.

To all whom it may concern:

Be it known that I, EDWARD R. MCKINZIE, a citizen of the United States, residing at Memphis, in the county of Shelby and State of Tennessee, have invented certain new and useful Improvements in Lock-Switches, of which the following is a specification.

My invention relates to improvements in lock switches, and the leading object of my invention is the provision of a switch which can only be operated by the person having the key of the proper shape and which can only be thrown in and out of operation by the use of the particular key.

Another object of my invention is the provision of a switch of the character mentioned which is particularly adapted for lighting purposes and which can be easily operated when necessary by the person having the desired key, and which will remain in locked condition except when in use for the desired purpose.

Another object of my invention is the provision of a switch of the character and for the purpose stated, which will be of simple, inexpensive and durable construction, which will occupy a small place and be of ornamental appearance, and which will be absolutely reliable and practical in operation.

With these objects in view, my invention consists of a lock switch embodying novel features of construction and combination of parts, substantially as shown, described and particularly defined by the claim.

Figure 1 represents a perspective view of a complete lock switch constructed in accordance with and embodying my invention. Fig. 2 represents a central sectional view with the operating parts of the switch shown in elevation. Fig. 3 represents a sectional view on the line 3—3 of Fig. 2. Fig. 4 represents a sectional view on the line 4—4 of Fig. 1, and Fig. 5 represents a perspective view of the operating key.

Referring by numerals to the drawing, in which similar characters of reference denote corresponding parts, in all the views: the numeral 1 designates the box or casing of my switch, which is of the proper shape and size, and has its chambered portion 2 covered by a suitable lid or cover 3, which is secured by the series of screws 4, and the box is fastened to the wall or structure by

means of suitable fastenings which pass 55 through the openings 5 in the box. In one end of the box or casing is formed the lateral recesses 6, which receive the wings 7, formed on the sleeve 8, the said sleeve having mounted therein the key post 9, formed with 60 the key slot 10, to receive the key 11, which key turns the said key post and is limited in its movement by means of the stop pins 12, which project from the disk 13, formed on the sleeve 8, abutting against the lug 9', 65 formed upon said key. From this construction it will be observed that the key post is permitted a limited movement and can only be operated by means of the key of particular construction, the lock being of the character known as Yale or Corbin locks, each of which must be operated by a particular key adapted to the certain lock, and this forms one of the important features of my invention, as it prevents the switch from being operated by other than the proper authorized person. The key post is formed at its upper end with an open head 14, the open portions receiving the insulating material 15, which when the switch is not in use bears upon the spring contact arms 16, connected with the plates 17, from which lead the service wires 18, protected by inclosing tubes 19, said tubes and the inclosed service wires being retained in proper place by the engaging 85 screws 20, passing through said screws and bearing upon said service wires 18, providing the proper contact for completing the circuit. The contact plates 16 are in the form of curved springs being disposed at a 90 right angle to the plates 17, and being either connected to or formed integral with the plates 17.

In normal position the parts of my switch occupy the relation shown in Fig. 2, and 95 when it is desired to operate the switch the key is inserted and the key post turned until the key is stopped by the pin 12, which movement brings the metal portion of the head in contact with the pair of contact 100 plates, thus completing the circuit and turning on the lights. If the switch is used for sounding a bell, the operation is exactly the same.

It is evident that I provide a lock switch 105 which can be instantly operated by the person having the key, which will be absolutely reliable in operation, which is very simple

and inexpensive in construction, and which from every point of view will prove thoroughly efficient and practical.

I claim:

5 A lock switch of the character described, consisting of the lock or casing having a chambered portion with a pair of small vertical passages at one side thereof and having an enlarged circular opening with communicating lateral recesses at the opposite side thereof, tubes for inclosing and protecting the service wires arranged in the said vertical passages, a pair of transverse passages leading to said vertical passages, binding screws passing through the tubes and engaging service wires, and having heads fitting in said transverse passages, a sleeve fitting in the circular opening and having wings secured in the said lateral recesses, a

key post mounted in said sleeve and carrying an open head at one end and a key receiving plate at its other end, means for limiting the movement of the key plate consisting of a pair of stop pins carried by the sleeve and adapted to be engaged by the key, curved spring contact plates secured in the casing and bearing against the open head of the key post and plates connected with the spring contact plates at one end and having their other ends connected with the service wires and fitting in the said service wire protecting tubes.

In testimony whereof I affix my signature in presence of two witnesses.

EDWARD ROSELL MCKINZIE.

Witnesses:

HEINRY BURKARD,

ALBERT B. GOODWIN.
